UNITED STATES PATENT OFFICE.

AUGUST WILL, OF JERSEY CITY, NEW JERSEY, ASSIGNOR TO DAVID WOLFE BRUCE, OF NEW YORK, N. Y.

DESIGN FOR A FONT OF PRINTING-TYPES.

SPECIFICATION forming part of Design No. 12,008, dated November 2, 1880.

Application filed August 20, 1880. Term of patent 14 years.

To all whom it may concern:

Be it known that I, AUGUST WILL, (assignor to DAVID WOLFE BRUCE,) of Jersey City, Hudson county, New Jersey, have invented and produced a new and original Design for a Font of Printing-Types, of which the following is a specification.

The nature of my design is clearly shown in the accompanying typographic impression; and it consists of a design for a font of printing-types to be used for the formation of borders and ornamental surroundings for printed matter.

I will now proceed to describe the various members of which the font is composed.

No. 1. This figure is bounded on the left by a semi-elliptical curve with scroll terminations connected by a serrated line. Between the scroll extremities is a curved line, terminating below in a scroll, and the space between this line and the serrated one is shaded by the parallel curves.

No. 2. The base of the figure is a semi-elliptical curve with scroll terminations connected by a smaller semi-elliptical curve, the space between the scrolls shaded by parallel curves, one terminating in a dot. Upon the upper right of this figure is placed a leaf, surmounted by a tendril terminating in the loops, as shown.

No. 3. The main portion of the figure is a semi-elliptical curve, broken upon the left by the leaf-like ornament curving outward, having the scroll terminations connected by semi-elliptical curve parallel to the outer one, below which is placed the curved tendril. From the right scroll extends upward and across the main curve a slender-stemmed scroll, above which and forming the upper portion of the figure is placed the semicircular tendril-like ornament.

No. 4 is a tendril with bifurcated extremity, with a row of dots curved to the right between the end tendrils; at the base of the tendril a pair of leaves.

No. 5. Upon the upper left of the figure is a pair of leaves. From between these extends to the right and upward and downward two much-looped tendrils, crossing each other. The tendrils are each ornamented by a pair of curved lines, those on the upper tendril terminating in a dot.

No. 6. The left portion of the figure is a semi-elliptical curve with scroll-like terminations, these connected by semi-elliptical curve parallel to the outer one, the right-hand portion of the figure composed of the curved body, proceeding from a dot, joining the left-hand portion of the figure about centrally, and terminating to the right in the scroll-like termination. From the scroll proceeds to the left a leaf-like ornament, from which proceeds upward to the dot a slender line, the compound figure crossed by the tendril having two loops upon the right, terminating upon the left in the dot, and adorned with a pair of leaves, also, upon the left.

No. 7. Upon the lower left of the figure is the semi-elliptical curve with scroll-like terminations, upon the right of which and above it and in the inclined position is placed a larger semi-elliptical curve, its upper portion broken by the leaf-like ornament curving outward, having the scroll terminations. From between the lower scroll and broken part of this figure proceeds a slender-stemmed bud, followed by the tendril, with two loops curved to the left. From the left of the figure proceeds the leaf-like ornament, and below the larger body is placed the curved line with dot terminations.

No. 8. Upon the upper right of the figure is a group of leaves, placed between and above a semi-elliptical curve with scroll-like terminations, connected by a line parallel with the outer curve upon the right, and the slender curved lines rising and terminating in the heavy dot upon the left. From the semi-elliptical curve upon the right proceeds the curved stem with bud-like ornament, to the right of which is placed the semi-elliptical curve, the extremities of which join this curved stem; the left portion of the figure, composed of the curved line, extending upward to the left and outward to form the leaf-like termination, and an upper curved line continuing from this leaf-like termination to the right, which is broken, forming the leaf-like ornaments, and finally curves to the right and downward, this portion of the figure surmounted by the semi-elliptical curve with scroll terminations connected by a line parallel with the outer curve, the upper line, which is curved downward to the right, met by a heavy line at its termination, curved upward and to the left, this connected by a light line to a heavy curved line terminating abruptly, from which proceeds, near its upper portion and upon the right, a spray ornamented by the leaves and followed by a lanceolate leaf, and upon the left of which are the dots following the configuration of this heavy curve.

No. 9. Upon the right of the figure is a semi-elliptical curve with scroll-like terminations connected by a line parallel to the outer curve. Below the figure, about centrally, is placed the leaf-like ornament, and the figure is shaded upon the left by a series of light and heavy lines. From this portion of the figure proceed seeds, about centrally, and drooping to the left, a branch of leaf and tendril like ornaments.

No. 10 is the reverse of No. 9.

No. 11. The base of the figure is a group of leaves, from which proceed to the right the light lines, curved and having the open dot terminations, also the light line with calyx-like termination; above this the four heavy dots, to the left of which is the light stem with flower-like ornament, followed by the stem with flower and bud like ornament, succeeded by the double-looped tendril upon the left, and the curved tendril with single loop below.

No. 12. The base of the figure is a group composed of the ovate leaves with lanceolate leaf between them; above this group of leaves a bifurcated tendril, the right-hand portion curved to the right and having a single loop, and the left-hand portion curved to the left and having two loops, as shown. Both the right and left hand portions of the tendril terminate abruptly. From the right-hand portion extends, near its union with the left-hand portion, the curved line with hook-like tip, and this ornamented by the three dots upon the right and the single dot upon the left.

No. 13. Upon the left of the figure is a semi-elliptical curve with scroll terminations connected by a line parallel with the outer curve. From the upper scroll proceeds to the right the leaf-like ornament, as shown, and the face of the figure is ornamented by the light and leavy lines. The lower portion of the semi-elliptical curve is ornamented upon the right by a curved line, terminating in a hook-like ornament upon the right, upon the left of which is placed a tendril with two loops. Upon the right of the semi-elliptical curve, and forming a continuation of the same, is placed a smaller semi-elliptical curve with scroll terminations connected by a line parallel with the outer curve, below which is placed a leaf-like ornament, and from which proceeds downward a curved line, which terminates upon the left in a scroll, and upon the upper side of the right-hand scroll of which is placed a tendril.

No. 14. Upon the left of the figure is a semi-elliptical curve with scroll terminations connected by a line parallel with the outer curve, below and upon the left of which is placed a curved line, terminating upon the right in a scroll the face of which is shaded. Upon the right of this semi-elliptical curve is placed a larger semi-elliptical curve with scroll terminations, the upper portion of which is shaded by the heavy curved lines and the face of the lower scroll ornamented by a leaf-like figure, followed by the dots, to the left of which is placed a slender curved stem with bud-like termination. Below this semi-elliptical curve is placed a leaf-like ornament, upon the left of which is placed a curved line, terminating in a ball-like ornament upon the left.

No. 15. Upon the right of the figure is a semi-elliptical curve with scroll-like terminations connected by the heavy line following the outer curve and shaded by a light line below it. To the left of this is placed a larger semi-elliptical curve with scroll-like terminations connected by a line parallel with the outer curve. From the lower scroll termination of this second figure extends downward and to the right a leaf and flower like ornament and upward and to the left the curved leaf ornament. From the leaf and flower like ornament upon the right extend upward and to the left the intertwined tendrils. From the leafed-like figure between the two semi-elliptical curves proceeds to the left a slender stem, crossing the larger semi-elliptical curve and bearing the leaves, as shown.

No. 16. The base of the figure is a scroll shaded upon the face by the heavy and light curved lines, as shown. Below this is placed a shaded semi-elliptical curve with scroll-like terminations connected by a line parallel with the outer curve. Upon the right of this is placed a two-looped tendril. From the upper portion of the scroll extends upward about centrally the curved shaded figure with scroll-like termination, and upon the left of this a second curved shaded body with scroll-like termination. In the space to the right of the left-hand scroll and the leaf-like figure is placed a tendril, and from the eye of the scroll to the right extends a slender stem bearing a leaf. Upon the left of the second shaded curved figure is placed a curved leaf-like figure, from which to the right, and crossing the smaller curved figure, extends the slender curved stem, terminating in the flower drooping to the right and the leafed tendril extending upward.

No. 17. The main portion of the figure is composed of the semi-elliptical shaded curve. The upper termination has the curved leaf shape and the lower termination scroll shape, as shown, the space between the terminations ornamented by the curved slender-stem flower-like ornament, followed by the curved much-looped tendril, having its termination in the leaf-like termination of the upper portion. From this scroll extends, also to the left, a curved stem bearing the leaves, and below this a slender stem bearing the leaves, crossing the central figure about centrally. From this portion of the figure also rises a scroll, above which is placed a looped tendril. Upon the left of the figure, proceeding to the left and upward, are a series of slender stems bearing leaves.

No. 18. Upon the left of this figure is a semi-elliptical curve, placed nearly vertically, with scroll-like terminations, from the lower one of which proceeds to the right and upward the curved leaf-like figure, having upon its left the scroll terminating at the left in the leaf-like ornament. Above it is placed the curved stem with leaves, followed by the many-looped tendril, extending upward and forming the left boundary of the upper scroll termination. From the upper scroll termination extend downward the curved lines, forming the shading of this portion of the figure. Upon the right of the figure extend upward from the lower scroll termination a group of curved slender stems, terminating in the leaf and bud like ornaments, the portions of the stems near the scroll shaded, as shown. From the dentated leaf upon the right extends a shaded curved figure with scroll-like terminations, from which proceeds upward and to the left the curved leaf-like stem, met by the slender stem proceeding from the base of the figure, this crossed in turn by the flower-like stem and flower proceeding from the lower scroll termination, and curved downward. The space between the group of stems upon the right and the semi-elliptical curve is filled by a leaf-like ornament surmounted by a shaded curved line.

No. 19. Upon the lower left of the figure rises a base with scroll-like termination, the lower line of which is curved and continued to the right and shaded below by a lighter line following its configuration. From the upper line of the figure proceeds to the right a second curved line, completing the boundary of the base; the space between the upper and lower boundaries shaded by a series of short horizontal lines extending about half-way across it, the upper bounding-line shaded by a light line following its configuration; this scroll-like base crossed by the upper scroll termination of a semi-elliptical curve placed in a vertical position, the rest of this figure projecting below the scroll-like base and terminating in the scroll-like ornament. From the eye of this scroll-like termination extend upward to the line of the base the heavy curved lines forming the left-hand boundary of this semi-elliptical curve. To the right, and below the scroll-like base, is the curved figure, having the leaf-like termination upon the left and the scroll-like termination upon the right, the leaf-like termination and lower side of the figure shaded by a series of short heavy lines. Above and to the right of this is placed the shaded curved figure, the left-hand termination of which is the scroll, and from the underline of which proceeds the leaf, drooping downward and to the right, and the right-hand termination of which is followed by the curved bud-like ornament, followed by the 70 tendril adorned with leaves and proceeding to the left and above the bud-like ornament. To the left of the left-hand scroll rises the bud-like ornament, and to the left of this, rising above the scroll-like base, is the semi-elliptical curve with scroll-like terminations connected by a line following the configuration of the outer curve, the face of which is shaded upon the right by a series of short horizontal lines, and from the curved line connecting the 80 terminations of which proceeds upward and to the right a slender stem adorned with the leaves and forming the left-hand boundary of the right-hand termination. The left-hand boundary of the left-hand portion of this figure is formed by the shaded leaf-like ornament, the lower portion of which rests upon the scroll-like base.

No. 20. The upper portion of the figure is a semi-elliptical curve with scroll-like terminations connected by a line following the configuration of the outer curve; the right-hand portion of the figure shaded by a series of heavy curved lines, filling this portion of the face, the face of the left-hand portion of the 95 figure adorned with the curved leaf-like figure. From the left-hand scroll termination proceeds to the right a bifid-like ornament, from the upper side of which proceeds a curved slender stem with bud-like termination, to the right 100 of which is placed a row of dots curved to the left, from the center of which proceeds to the right and upward a leaf-like figure, and from the lower portion of which proceeds to the right and downward a flower-like ornament 105 succeeded by a slender stem with bud-like termination, the space between the bud and leaf adorned by a series of heavy dots. A short distance below this figure is placed a second semi-elliptical curve with scroll-like 110 terminations connected by a broken line partially following the outer curve, the face of the figure shaded by a series of heavy curved lines. Upon the left of this figure is placed a semi-elliptical curve, the upper termination of which 115 is scroll-like, its lower termination leaf-like, the connecting-line between the terminations being broken at its lower part to give this appearance. Below this figure is placed a bifurcated tendril. The space between the two 120 larger semi-elliptical curves is filled by the leafy ornament continued to form the left-hand boundary of the main semi-elliptical curve.

No. 21. The main portion of the figure is composed of a group of stems with leaf, bud, and flower like ornaments. Upon the right of the figure rises the slender stem, curling to the right, and adorned with the leaves at intervals, as shown, and having a leaf termination. From this portion of the figure proceeds upward the looped tendril; upon the left of the figure a leaf-like ornament, beyond which are the slender stems with leaf and bud like ornaments.

No. 22 is the reverse of No. 21.

No. 23. The central portion of the figure is a semi-elliptical curve with scroll-like terminations connected by a line parallel with the outer curve; the face of the figure shaded upon the right by a series of short heavy lines, the scroll termination upon the left ornamented by the leaf-like figure, the central figure also ornamented by the leaf-like figure extending below it. From the eye of the scroll upon the left proceeds outward and to the left the curved figure with scroll-like termination, the face of the scroll portion ornamented by the curved leaf-like ornament and the rest of the face of the figure ornamented by the stems with leaf-like terminations. The central figure is crossed upon the right by a semi-elliptical curve with scroll-like terminations, from the upper termination of which proceeds above it the curved leaf-like figure, and below and extending beyond the lower termination the curved figure with leaf-like ornament upon the left, and from which proceeds upward the curved figure with ball-like termination. Above the central figure is the shaded groundwork formed of a series of curved lines, the upper one terminating in the scroll upon the right. From this proceeds to the left the curved line with sickle-like termination, from which proceeds to the right the curved leaf-like figure ornamented by the curved tendril provided with the leaves, as shown.

No. 24. Upon the left of the figure is a semi-elliptical curve with scroll-like terminations connected by a line parallel with the outer curve, the face shaded by the curved lines, as shown, below which depends about centrally the smaller semi-elliptical curve with scroll-like terminations connected by a line parallel with the outer curve. Upon the right of the lower scroll termination is placed a curved figure, the upper termination being scroll-shaped, shaded by a series of fine curved lines without it, and from which proceeds to the right a curved tendril provided with the leaves, the lower termination scroll-like and its face shaded by the leaf-like figures. Above this portion of the figure and covering the semi-elliptical curve is the curved figure with scroll-like terminations, the left-hand one of which projects downward. The space between the upper scrolls of the two figures is ornamented by a semi-elliptical curve with scroll-like terminations connected by a line following the configuration of the outer curve, the left-hand portion shaded on its face by a series of curved lines and ornamented by the leaf-like ornament placed within and connected to the upper scroll by a shaded semi-elliptical curve, having a scroll-like termination above and a curved leaf-like termination below, curved to the left.

No. 25. At the base of the figure, upon the left, is a shaded curved figure having the scroll termination above and the curved leaf termination below, this followed by a scroll-like figure, from the lower scroll termination of which proceeds to the left the leaf-like figure, crossing the line of the curved figure below. From the eye of the upper scroll termination proceeds a shaded curved figure, terminating upon the right in the scroll termination; below this figure, from the eye of the scroll, a group of stems bearing leaves, followed upon the right by the curved stem bearing leaves, and above the figure, about centrally, projects the slender-stem leaf-bearing figure. Above the right-hand scroll termination is placed the semi-elliptical curve with scroll-like terminations connected by a line parallel with the outer curve, the face shaded by a series of curved lines. To the right of this figure is placed a shaded curved leaf-like figure having a scroll termination upon the right, below which is placed the leaf-like figure, as shown.

No. 27 is an escutcheon-like figure partially shaded by the short horizontal lines near the bounding-lines of the figure; upon the lower right corner the figure ornamented by the semi-elliptical curve with scroll-like terminations connected by a line parallel with the outer curve; above, the line of the figure continued upon the right to form the scroll-like termination shaded upon its face by the short heavy - and light lines. Upon the left of the figure is placed the semi-elliptical curve with scroll-like terminations connected by a line parallel with the outer curve, the face of which and the 5 lower scroll shaded by the heavy curved lines; above this, figure following its configuration for a portion of its length, and projecting beyond it, upon the left, is the curved body with scroll-like termination, the lower line of the 10 figure ornamented about centrally by the leafy ornament. Below the scroll termination is placed the tendril provided with two pairs of leaves. Beyond, above, and to the left of this curved figure with scroll termination extends 15 the curved leaf-like ornament, the termination curved to the right. The upper line of the figure is broken to form the curved leaf-like ornaments, from the right-hand one of which projects upward the looped tendril, and the 20 face of the figure ornamented by the leaf-bearing stem extending downward from this leaf ornament; the right-hand boundary of this portion of the figure formed of the curved leaf-bearing tendril proceeding upward from the 25 scroll termination of a semi-elliptical curve, the opposite termination of which is scroll-like, and the center of which is crossed by a slender stem with leafy termination proceeding from the shaded curved figure.

- 30 No. 28. The base of the figure is a semi-elliptical curve with scroll-like terminations connected by a line parallel with the outer curve, shaded upon its face by the heavy curved lines, the space between the scroll terminations ornamented by the curved tendril with leaves, which 35 extends below the lower scroll termination. Above and to the right of this extends the curved shaded leaf-like figure, and the upper right-hand corner of the figure is ornamented 40 by the curved shaded scroll-like ornament curved to the left, the space between the leaf and scroll-like ornament filled by a shaded leaf-like figure, to the right of which and the scroll-like ornament is the much-looped curved tendril, extending from the lower leaf-like termination upward. The portion of the figure 45 above and to the left of the base near its boundary-lines is shaded by the short vertical lines. From the shaded ring-like ornament ornamenting the face proceeds to the left a shaded stem, with leaf-like termination curling around the boundary-line, and the curved shaded stem with leaves terminating in a scroll-like termination surmounted by a looped tendril. From 50 this stem also proceeds to the left, below the curved termination, a curved leaf-like figure, and to the left, forming the upper left termination of the figure, a curved shaded leaf-like figure.
- 55 No. 29. The base of the figure is a semi-elliptical curve with scroll-like terminations. The right-hand scroll termination has upon its left a leaf-like figure with dot termination; the face of this portion of the figure ornamented by a series 60 of small dots rising above each other and curved as they rise, the face of the curved figure for the greater portion of its extent shaded by the leaf-like ornament and the fine horizontal lines. Above this figure is placed 70 a smaller semi-elliptical curve with scroll terminations connected by a line parallel with the outer curve, below and to the right of which is placed a shaded curved line with scroll-like termination, this portion of the figure ornamented about centrally by the dentated leaves 75 projecting from the curved line connecting the terminations. Upon the left of the left-hand scroll-like termination, and joining it, is placed the small semi-elliptical curve with scroll-like 80 terminations connected by a line parallel with the outer curve, above which upon the right, and to the right of the left-hand scroll, is placed a bifurcated leaf-bearing stem. This smaller semi-elliptical curve is joined upon the right 85 by a curved figure with scroll-like termination at its upper end, shaded upon the left by the heavy curved lines. From the scroll termination curves outward and to the right a two-looped tendril, and upon its left a leaf-like ornament curved downward. To the left of the 90 base of the figure is placed a scroll-like figure, the right scroll termination of which crosses the base of the figure, and the boundary-line of which is broken at this point to form the leaf-like ornament, while the scroll termination at the left turns inward to the right, and from it proceeds a bifurcated tendril with looped termination, succeeded below and to the right by a curved leaf-like stem with leafy termination 95 curved to the left, below which is a group of fine dots rising above each other, followed by a curved stem with leaf-like termination. The face of the figure below the small semi-elliptical curve is shaded by the light vertical and 100 heavy inclined lines.
- No. 30. The base of the figure is a semi-elliptical curve having a curved leaf-like ornament upon the left and a scroll-like termination upon the right, the face of the figure shaded 110 by the heavy and light lines. Upon the right, and forming, as it were, a continuation of the same, is a series of curved leaf-like ornaments, the stems of which proceed from the scroll figure upon the right, the scroll having upon 115 the right the slender stem with dot termination, above it the flower-like ornament, and below and to the left the curved line with dot termination. Above the base is placed a second semi-elliptical curve with scroll terminations, 120 the face of which is shaded by the curved lines; the heavy curved stem with leaf-like termination curved upward, the heavy flower-like ornament curved downward and above by the slender curved stems with leaf-like ornaments 125 which proceed from the outer boundary of the figure. Upon the right of the right scroll is placed a semi-elliptical curve with scroll terminations connected by a line parallel with the outer curve, from which proceeds to the 130 right a figure formed by the lines curved inward about centrally and united at the opposite ends by a ring-like figure. Above this figure is placed a double-looped tendril, and the space below is shaded by the heavy curved lines. The base of the figure upon the right 5 and the curved leaf figure upon the right are connected by a semi-elliptical curved figure with scroll-like terminations; the face of the figure upon the left of the heavy curved lines ornamented by a figure composed of a short, 10 heavy, inclined line, from the left termination of which proceeds a curved line and upon the left a heavy curved line, both shaded above and upon the right by a series of light lines following the configuration of the figure. 15 No. 31. The base of the figure is a semi-elliptical curve with scroll-like terminations connected by a line parallel with the outer curve, below which is placed, running from the right to about the center of the figure, a 20 curved leaf-like figure. The face of the figure is shaded by the curved stems with leaf-like terminations. The left-hand scroll termination is shaded upon the right by the looped tendril below and the leaf and flower-like ornaments 25 above, the right-hand scroll termination by the leaf-like figure following its configuration, and is bounded by a semi-elliptical curve with scroll-like terminations connected by a line parallel with the outer curve, the figure sur- 30 mounted by the leaf-like figure following the curve of the main figure and shaded, as shown, upon the left of which is placed the shaded scroll termination. Above the leaf-like ornament upon the left is placed a shaded semi- 35 elliptical curve with scroll-like terminations, the right-hand scroll crossing the leaf-like figure and the left-hand scroll crossed by a looped tendril continued beyond the scroll to the left. To the left and above this figure a third semi- 40 elliptical curve is placed, the terminations being scroll-like, connected by a line parallel with the outer curve, and below the right scroll of which is placed the flower-like ornament. To the right of the right-hand scroll termina- 45 tion rises from the leaf-like figure a shaded curved leaf-like figure curved to the left, followed by a thin shaded leaf-like figure. Upon the right the leaf-like boundary of the figure is surmounted by a shaded semi-elliptical 50 curve with scroll-like terminations, from the left-hand scroll of which curves upward and to the left the shaded leaf-like figure, from which proceeds upward, curving to the right, the curved stem with leaf-like termination; 55 the curved stem with flower, and curved line with dot termination, crossed by the curved stem with leaf-like figure, and upon the right of which is placed the fine tendril looped. The semi-elliptical curve is surmounted by a much- 60 looped tendril, and is crossed by the curved shaded leaf-like ornament proceeding from the leaf-like boundary of the main figure, while it is ornamented by the flower-like ornament, its upper portion ornamented by the slender stem with leaf and flower-like ornament. This 65 curved leaf-like ornament is continued upon the right of the figure, and has the scroll-like termination, and near this scroll termination is ornamented by two semi-elliptical curves with scroll-like terminations placed above it 70 and joined together, as shown. Upon the base of this combined figure formed of the two semi-elliptical curves are the flower and leaf like ornaments, followed by a looped tendril above the second semi-elliptical curve. 75

No. 32. The base of the figure is a semi-elliptical curve with scroll-like terminations, the right one and face shaded by the light curved lines and leaf-like ornaments, the line connecting the scrolls ornamented about centrally by 80 a leaf-like figure; the figure surmounted by a shaded leaf-like figure extending round the left-hand scroll and upon the right of the left-hand scroll, the latter ornamented upon the left by a leaf-like ornament surmounted by 85 the tendril with a pair of leaves. To the right of the leaf-like boundary upon the right is placed the scroll-like termination, the face of which is shaded by the vertical lines. Above and to the right of the leaf-like boundary is 90 placed a semi-elliptical curve with scroll-like terminations, the left-hand one of which crosses the leaf-like boundary, and the right-hand one of which is shaded upon the left by the lines following the configuration of the scroll. The 95 left-hand portion of the face of the curve is shaded by the light curved lines. To the left of this rises from the leaf-like boundary a leaf-like figure curved to the right, followed by a curved leaf-like figure with scroll termination, 100 below which is placed a semi-elliptical curve with scroll-like terminations connected by a line parallel with the outer curve, below the left-hand scroll termination of which is a flower-like ornament, from which proceeds a looped 105 tendril. To the right of and below the leaf-like boundary of the left hand scroll is placed a semi-elliptical curve with scroll-like terminations connected by a line parallel with the outer curve, the face of which is shaded by the 110 curved lines. To the left of the figure is placed a curved figure shaded on its face, the left-hand termination scroll-like, and its upper termination the shaded curved leaf form, followed by a flower and looped tendril curling downward and upon the left. This curved figure, 115 near its scroll termination upon the left, is intertwined with a semi-elliptical curve with scroll-like terminations connected by a line parallel with the outer curve, the face of which is shaded, and having above it a semi-elliptical curve with scroll-like terminations connected by a line parallel with the outer curve, shaded upon its face, ornamented below by a flower-like ornament crossing its face, and above by 120 a bifurcated tendril provided with the leaves and loops, as shown. The curved figure is also crossed by the left-hand scroll of the semi-elliptical curve extending to the right, and having the scroll termination upon the 125 right, its face shaded by the curved lines. From the left-hand scroll of this figure proceeds upward, crossing the curved portion of the figure, a slender stem provided with the leaves, succeeded by a much-looped tendril curling to the right. From the right-hand scroll of the figure proceeds a group of curved dentated leaves, and a curved stem with dot-like termination, from which stem proceeds a looped tendril followed by a shaded leaf-like figure.

- 10 No. 33. The base of the figure is a semi-elliptical curve upon the left, with scroll-like terminations connected by a line parallel with the outer curve, followed by a larger semi-elliptical curve with scroll-like termination upon the 15 right, and shaded upon its face by the curved lines; these figures connected by a short heavy figure, the left scroll-like termination shaded on the right by a curved leaf, followed by a looped tendril, the right-hand scroll shaded 20 upon the left by a leaf and bifurcated tendril provided with the leaves; the upper boundary of these figures a leaf-like figure shaded upon its face and above at intervals by the heavy lines following its configuration. To 25 the left of the left-hand scroll proceeds from a second scroll-like termination a curved leaf shaded upon the upper portion of its face, curved downward and to the right; to the left of this the scroll-like termination of the 30 scroll-like figure, extending upward and to the right, and having a scroll-like termination, this shaded by a series of light curved lines, and near its upper termination by the short inclined lines. From the eye of the upper scroll 35 proceeds to the left the curved leaf figure, and, also curving to the left and passing over the upper scroll termination, the curved leaf figure followed by a scroll termination. From the outer boundary of this scroll figure rises 40 a group of curved leaves, from the lower one of which proceeds a curved much-looped tendril, forming the left boundary of the figure, and the central loop a slender stem bearing leaves, followed by a flower-like ornament, from the right of which proceeds the looped 45 tendril. To the left of the upper scroll are placed a series of heavy curved lines, terminating in the left scroll termination of the semi-elliptical curve with scroll terminations, from the right of which proceeds to the left a 50 curved figure with scroll termination, shaded and ornamented by the leaf and tendril figures; the space between this figure and a semi-elliptical curve with scroll terminations placed at the lower right of the figure filled by the 55 shaded leaf-like figure to the right, and having its outer boundary shaded by the heavy lines, as shown, following its configuration. The upper scroll of the lower right semi-elliptical curve is shaded by the heavy curved lines, 60 as shown, while from the lower scroll termination proceeds the leaf-like figure, followed by a tendril provided with leaves and dots.

No. 34 differs from No. 33, of which it may be said in other respects to be the reverse, as follows: the semi-elliptical curve at the lower left ornamented by a curved leaf figure having a two-looped tendril above it; the space to the right of the left-hand leaf-like boundary ornamented by the curved leaves; the curved 70 figure with scroll termination, to the right of which proceeds the bud and two-looped tendril; and the leaf-like ornament added to the flower-like ornament upon the right above the figure, instead of the tendril.

Having now described my invention, I 75 claim—

The design for a font of printing-types, substantially as shown and described.
